(57) **CLAIM**

The ornamental design for a tail for a flying toy, as shown and described.

DESCRIPTION

FIG. 1 is a front, top and right side perspective view of the new design shown connected as part of an exemplary flying toy to illustrate its immediate environment;

FIG. 2 is a magnified view of FIG. 1 without the environment;

FIG. 3 is a rear, bottom and left side perspective view thereof;

FIG. 4 is a front elevational view thereof;

FIG. 5 is a right side elevational view thereof;

FIG. 6 is a rear view elevational view thereof;

FIG. 7 is a left side elevational view thereof;

FIG. 8 is a top plan view thereof; and,

FIG. 9 is a bottom plan view thereof.

The concave broken outline portions define the bounds of the claim immediately adjacent the shaded area at the front end of the tail. All other broken lines are shown only for the purpose of illustrating the environment of the design. None of the broken lines form part of the claim.
